UNITED STATES PATENT OFFICE.

SAMUEL E. KEENER AND WILLIAM A. MUNSON, OF CLAY CENTER, KANSAS.

WINDMILL.

No. 852,275.

Specification of Letters Patent.

Patented April 30, 1907.

Application filed May 22, 1905. Serial No. 261,495.

To all whom it may concern:

Be it known that we, SAMUEL E. KEENER and WILLIAM A. MUNSON, both citizens of the United States, residing at Clay Center, in 5 the county of Clay and State of Kansas, have invented certain new and useful Improvements in Windmills, of which the following is a specification.

Our invention relates to the operating 10 mechanism of vertical windmills and the objects are to simplify and strengthen the construction and steady the running of the windmill.

That our improvements may be the more 15 readily understood and for a more detailed description thereof reference is had herein to the accompanying drawings, in which,—

Figure 1 is a perspective view of a windmill showing our improved mechanism, Fig. 2 is 20 a plan in section showing the relative location of the respective parts of our device, Fig. 3, a vertical section of the same and Fig. 25 4, a perspective view in detail showing the guide- and reciprocating-rods in their respective relation to the slotted cross-head in connection with which our device operates as hereinafter set forth.

Similar figures of reference indicate like parts throughout the several views.

The windmill may be of the ordinary well 30 known construction of the vertical class.

In the windmill shown,—1 refers to the blades or sails of the wind-wheel, 2 to the reciprocating-rod connecting with and operating 35 the pump or other machinery, 3 to the shaft of the wind-wheel, 4 to the spur-pinions secured to said shaft 3, one on either side of said reciprocating-rod and meshing with gear-wheels 6 6 similarly located and 40 connected with each other by eccentric-pin 7 passing through the horizontal slot 26 in the jointed cross-head 24. The journals 5 5 of said gear-wheels 6 6 have their bearings in opposite sides of the frame-work 10 and 45 guide-rod 8 passes through bushing 9 in the

head of said frame-work. Attached to said frame-work at its base 12 is the casing 11 through which extends the reciprocating-rod 2 and, generally, the usual cable or cord by which the fan or vane 16 is thrown out of or 50 into the wind.

We preferably construct our windmill with the guide-rod 8 midway of the cross-head 24, as shown in Fig. 4; but it may be placed vertically opposite the reciprocating-rod, as 55 shown in Fig. 3.

We are aware of the use of the double-crank with the gear-wheel secured to one shaft, the wrist passing through the slot in the cross-head and the other shaft journaled in the opposite side of the frame-work and it is particularly upon that type of windmill we claim to have improved by the substitution for said crank of duplicate pinions and gear-wheels and connecting the latter with the eccentric-pin, as herein shown and described; thus securing a uniform and steady motion and materially strengthening the construction of the operating mechanism.

Having thus described our invention, what 70 we claim as new and desire to secure by Letters-Patent is,—

In a windmill, the combination with a supporting frame, of a shaft journaled therein and carrying a pair of pinions, a pair of alined stud snails journaled in the frame carrying gears which mesh with said pinions, a crank rod connecting said gears, said rod consisting of a straight bar having its ends connected to the gears, and a reciprocating rod having 80 a slotted cross head in which said crank rod travels, and guides for said reciprocating rod.

In testimony whereof we have affixed our signatures hereto in the presence of two witnesses.

SAMUEL E. KEENER.
WILLIAM A. MUNSON.
